UNITED STATES PATENT OFFICE.

NORRIS E. GOODRICH, OF BATTLE CREEK, MICHIGAN, ASSIGNOR TO SANITARIUM AND HOSPITAL EQUIPMENT CO., OF BATTLE CREEK, MICHIGAN.

ELECTRIC PAD OR BLANKET.

Application filed January 26, 1925. Serial No. 4,940.

This invention relates to improvements in electric pads or blankets.

The main object of this invention is to provide an improved electric pad or blanket which is very flexible and may be repeatedly flexed without liability of injury to the resistance wires embodied in the heating element thereof.

Objects pertaining to details and economies of my invention will definitely appear from the detailed description to follow.

I accomplish the objects of my invention by the devices and means described in the following specification. The invention is clearly defined and pointed out in the claims.

A structure illustrating my invention is clearly illustrated in the accompanying drawing forming a part of this application, in which:

Fig. I is a perspective view of a heating pad or blanket embodying the features of my invention.

Fig. II is a fragmentary view illustrating details of the heating element, the same being in section on a line corresponding to line 2-2 of Fig. I.

Fig. III is a fragmentary plan view with a portion of the casing removed.

Fig. IV is a diagrammatic view of the heating element and the connections thereto to the switch.

In the drawing the sectional views are taken looking in the direction of the little arrows at the ends of the section lines and similar numerals of reference indicate similar parts in all of the views.

Referring to the drawing, my improved pad or blanket comprises a casing 1 of textile material in which the heating element designated generally by the numeral 2 is enclosed. This heating element is in the general form of a woven fabric consisting of the warp strands 3 of textile material and the continuous woof strand 4 which is interwoven back and forth with the warp strands.

This woof strand comprises a plurality of fine flexible resistance wires 5 enclosed within a tubular casing 6 of insulating material. These fine resistance wires not only provide a very efficient heating element but one which is very flexible and capable of being repeatedly flexed without liability of breaking the strands of wire. The strands being

enclosed by the relatively thick tubular casing 6 prevents sharp bends or knots in the resistance wires. The resistance wires or strands are all connected to the circuit wires as a unit.

In the structure illustrated the circuit wires 7 and 8 are connected to the ends of the heating unit wires or strands while the circuit wire 9 is connected to a central loop 10 thereof through a resistance coil 11, the object being to provide means for controlling the heating of the pad. These circuit wires are controlled by a switch which in the structure illustrated consists of a base member 12 and a top adjustable member 13. These members are casing-like in form and enclose the switch mechanism which is connected to the supply circuit wires 24.

As the details of the switch mechanism form no part of this invention they are not further illustrated or described.

Having thus described my invention what I claim as new and desire to secure by Letters Patent is:

1. In a structure of the class described, the combination with an outer flexible casing of textile material, a heating element in the form of a woven fabric comprising warp strands of textile material, a continuous woof strand interwoven with said warp strands and comprising a plurality of fine flexible resistance wires enclosed in a flexible continuous tubular casing of insulating material, and circuit wires operatively connected to said resistance wires.

2. A heating element for electric pads or blankets in the form of a woven fabric comprising warp strands, a continuous woof strand interwoven with said warp strands and comprising a plurality of fine flexible resistance wires enclosed in a flexible strand-like casing, and circuit wires operatively connected to said resistance wires.

3. A heating element for electric pads or blankets in the form of a woven fabric comprising warp strands and a continuous woof strand interwoven with said warp strands and comprising a plurality of fine resistance wires enclosed in a flexible tubular casing having relatively thick walls preventing sharp bends or knots of the resistance wires.

In witness whereof I have hereunto set my hand.

NORRIS E. GOODRICH.
